UNITED STATES PATENT OFFICE.

EDWARD BRUNHOFF, OF CINCINNATI, OHIO.

DESIGN FOR A CHANGE-TRAY.

47,129.

Specification for Design.

Patented Mar. 23, 1915.

Application filed October 15, 1914. Serial No. 866,868. Term of patent 7 years.

To all whom it may concern:

Be it known that I, EDWARD BRUNHOFF, a citizen of the United States, residing at Cincinnati, in the county of Hamilton and State of Ohio, have invented a new, original, and ornamental Design for Change-Trays, of which the following is a specification, reference being had to the accompanying drawings, forming a part thereof.

My new and original design comprises, as illustrated a hollow body exteriorly of rectangular outline at the base with slightly inwardly sloping side and rear walls, and a more sharply sloping front wall. The upper face presents a raised marginal line, and a broad rectangular inclined face encompassed by said marginal line, and curved upwardly

at the sides and front to meet said marginal line, and with a trough shaped depression with curved ends, across the front at the lower terminus of said inclined top face.

Figure 1 of the drawings is a perspective view, and; Fig. 2 is a central vertical section from front to rear through Fig. 1.

I claim:

The ornamental design for a change tray as shown and described.

In testimony whereof, I have affixed my signature in the presence of two witnesses.

EDWARD BRUNHOFF.

Witnesses:

C. W. MILES,
W. THORNTON BOGERT.
